CLAIM

We claim the ornamental design for a shower wand and adjustable mount, as shown and described.

DESCRIPTION

FIG. 1 is a front view of a shower wand and adjustable mount in a straight position.

FIG. 2 is a rear view of the shower wand and adjustable mount in the straight position.

FIG. 3 is a bottom view of the shower wand and adjustable mount in the straight position.

FIG. 4 is a top view of the shower wand and adjustable mount in the straight position.

FIG. 5 is a right side view of the shower wand and adjustable mount in the straight position.

FIG. 6 is an upper-right-front perspective view of the shower wand and adjustable mount in the straight position.

FIG. 7 is a right side view of the top portion in angled position.

FIG. 8 is an upper-right-front perspective view of the shower wand and adjustable mount in the angled and rotated position.

FIG. 9 is a front view of the shower wand removed from the adjustable mount.

FIG. 10 is a rear view of the shower wand removed from the adjustable mount.

FIG. 11 is a right side view of the shower wand removed from the adjustable mount.

FIG. 12 is an upper-right-front perspective view of the shower wand removed from the adjustable mount; and,

FIG. 13 is an exploded right, front perspective view. The broken line showing in FIGS. 2-5 and 7 is included for the purpose of illustrating environment and forms no part of the claimed design.
